[57] CLAIM

The ornamental design for an extendable toy car or similar article, as shown and described.

DESCRIPTION

FIG. 1 is a perspective view of an extendable toy car showing our new design;

FIG. 2 is a right side elevational view thereof;

FIG. 3 is a top plan view thereof;

FIG. 4 is a left side elevational view thereof;

FIG. 5 is a bottom plan view thereof;

FIG. 6 is a front elevational view thereof;

FIG. 7 is a rear elevational view thereof; and,

FIG. 8 is another front perspective view thereof, with the design in an extended position.

FIG. 6

FIG. 7
